INVENTOR

United States Patent Office.

JOHN N. LEONARD, OF ROCKVILLE, CONNECTICUT.

Letters Patent No. 92,618, dated July 13, 1869.

IMPROVED SPOOL-SHOW-CASE.

The Schedule referred to in these Letters Patent and making part of the same.

To all whom it may concern:

Be it known that I, JOHN N. LEONARD, of the village of Rockville, county of Tolland, and State of Connecticut, have made certain new and useful Improvements in Apparatus for Displaying Spool Sewing-Silks, Machine-Twist, Cotton and Linen Threads, &c.; and I do hereby declare that the following is a full and exact description thereof, enabling others skilled in the art to make and use the same, reference being had to the accompanying drawings, in which—

Figure 1 is a vertical section through the line *x x*;

Figure 2, a perspective view; and

Figure 3, section through line *z z*.

Construction.

A is a revolving spool-like beam, consisting of a pair of disk-wheels, rigidly attached, one at each end of an enlarged shaft, through which is passed and fastened a smaller shaft, *B*, which extends through the heads *C* and *D*, to wheel or lever *E*, affording there a means of operating *A*.

F F are the trays, which are designed to hold the goods for display, which are suspended, (at each end,) at their upper extremity, by means of an eye, which fits loosely over a stationary pin, *H*, on the inner face, and near the outer edge of the disk-wheels.

By this means, the rotation of *A* does not upset the trays *F*, (which are necessarily narrow, to show as much of the goods that are upon them as possible,) but allows them, by their own gravity, to remain at all times the same side up.

The base, *G*, is provided with drawers, for the accommodation of such articles as could not be conveniently or advantageously displayed upon the trays.

Above the base, the outside shell or case *I* is of cylinder-form, provided at the top with a revolving

cover, *J*, which oscillates upon the shaft *B*, by means of its heads *C C* and shaft *K*, which fits over shaft *B*, and extends through either head, *D D*, and through one head *D* far enough to admit of wheel *L*, by which means the cover *J* may be thrown open or shut at pleasure.

The size of the apparatus, and number of trays employed, depend altogether on the amount of different styles of goods to be displayed, heads *D D* affording bearing for shaft *K*, (through which passes and rotates shaft *B*,) besides closing both ends of case *I*, so that it has but one opening, which is at *J*.

Operation.

By means of hand-wheel *L*, cover *J* is thrown back, (opened,) exposing the trays, with goods which happen to be at the upper portion of the disk-wheel. If the desired color or style does not make its appearance at that point, beam *A* is revolved by means of wheel *E*, bringing each and every tray, and its contents, to the point of observation, after which cover *J* is thrown forward (closed) by the same means as opened, protecting its contents from the circulating of air, light, dust, &c.

Claim.

What I claim as my invention, and desire to secure by Letters Patent of the United States, is—

The suspended trays *F*, in combination with revolving beam *A*, cover *J*, and hollow shaft *K*, operated and arranged substantially as described.

J. N. LEONARD.
